UNITED STATES PATENT OFFICE

172,493

DRESS ENSEMBLE

Nat Chasser, New York, N. Y.

Application September 28, 1953, Serial No. 26,974

Term of patent 7 years

(Cl. D3—26)

To all whom it may concern:

Be it known that I, Nat Chasser, a citizen of the United States and resident of New York, in the county of Queens, State of New York, have invented a new, original, and ornamental Design for a Dress Ensemble, of which the following is a specification, reference being had to the accompanying drawings, forming a part thereof, and of which—

Fig. 1 is a front view of a dress ensemble, showing my new design;

Fig. 2 is a rear view of Fig. 1;

Fig. 3 is a front view of the dress member of the ensemble shown in Fig. 1 with the side panels of the skirt buttoned in the front;

Fig. 4 is a rear view of Fig. 3;

Fig. 5 is a front view of the dress member of the ensemble shown in Fig. 1 with the side panels buttoned in the rear;

Fig. 6 is a rear view of Fig. 5;

Fig. 7 is a front plan view of the dress member of the ensemble shown in Fig. 1 with the side panels extended; and

Fig. 8 is a rear view of Fig. 7.

I claim:

The ornamental design for a dress ensemble, as shown.
